UNITED STATES PATENT OFFICE.

WILLIAM A. GALLOWAY AND ALFRED Z. SMITH, OF XENIA, OHIO; SAID SMITH ASSIGNOR TO SAID GALLOWAY.

CORN-HARVESTER.

SPECIFICATION forming part of Letters Patent No. 601,248, dated March 29, 1898.

Application filed September 10, 1895. Serial No. 562,080. (No model.)

To all whom it may concern:

Be it known that we, WILLIAM A. GALLOWAY and ALFRED Z. SMITH, citizens of the United States, residing at Xenia, in the county 5 of Greene, State of Ohio, have invented certain new and useful Improvements in Corn-Harvesters; and we do hereby declare the following to be a full, clear, and exact description of the invention, such as will enable others 10 skilled in the art to which it appertains to make and use the same.

Our invention relates to corn-harvesters in general, and more particularly to that class intended for harvesting corn, cane, &c., whether 15 employed in connection with a binder or not, though in practice it has been found to be more economical to both reap and bind with a single machine.

One object of our invention is to raise fallen 20 corn in order that it may be cut at the proper point above its roots and thus insure the harvesting of the full crop. Moreover, when in an inclined position the stalk is much more difficult to cut.

25 A further object of our invention is to treat the stalks before they are acted upon by the cutter-knives in such a manner that the latter may readily cut the stalks. To accomplish this latter object, we arrange in front 30 of and in such positions as will crush the stalks at the points of engagement of the cutter-knives crushing-rolls, which may be provided with milled edges to facilitate their operation.

35 As will be readily understood, the nature of a cornstalk is such that it is splintered or crushed both above and below the points of engagement of the crushing means to a sufficient extent to allow the ready cutting of the 40 stalk by engagement of the cutters above and below the actual point of engagement of the crushing mechanism, as well as where thus engaged.

Referring now to the drawings, in which like 45 symbols of reference indicate similar parts in the several views, Figure 1 is a plan view of a harvester-frame provided with our improved mechanism for erecting and cutting the cornstalks, said frame having also the 50 usual elevating-chains arranged to convey the cut stalks to the binder mechanism. Fig. 2

is a side view taken at right angles to Fig. 1. Fig. 3 is a vertical cross-section of a picker-wheel having adjustable fingers.

Referring now to the drawings, 5 is the usual 55 harvester, upon which is mounted in suitable bearings the drive-shaft 6, having connection through the medium of a crank-disk 7, pitman 8, and slide-bar 9 with a reciprocatory knife 10, said bar 9 being adapted to slide in 60 suitable ways in the front portion of the frame, as indicated at 8' and 9'. This knife is preferably triangular in form, as shown, and works in conjunction with the blades 11 and 12 of a fixed knife secured to the adjacent portion 65 of the frame.

In order to cause engagement of the knives 11 and 12 and 10 and the stalks of a row of corn, we have provided certain means for first raising slightly such stalks as may lie against 70 the ground, then further raising such stalks and such stalks as may be at an angle to the ground, and then maintaining the upright position of the stalks and afterward altering their structure by crushing in such manner 75 that they may be more readily cut by the knives. To accomplish this purpose, beams 13 and 14 are pivotally connected with the frame 5 in such manner that they may have independent vertical movement relative to 80 each other and to the frame, the outer end of each beam being supported by a pivoted caster-wheel 15.

To the front end of each beam 13 and 14 and projecting downwardly and forwardly 85 therefrom to enter beneath fallen stalks is attached a snout 16 and 17, respectively, of the usual construction, which snouts raise the fallen corn to a position to be engaged by the picker-wheels 18 and 19, which latter are provided with inwardly-curved fingers and are journaled in suitable bearings on the inner sides of the beams 13 and 14. These picker-wheels have a parallel arrangement and are positioned so far apart as to allow the passage 95 of a row of corn between their adjacent faces, the fingers 20 thereon being turned inwardly to an extent to lift the fallen corn to an upright position. The extent of inward movement of these fingers, it will be readily understood, will depend upon the condition of the corn operated upon—that is, the direc- 100

tion in which the fallen corn lies—said fingers being adjustably secured in place to enable this adjustment, as will be more readily appreciated when referred to later.

5 Secured to the beams 13 and 14 are forward uprights 21 and 22 and rearward uprights 23 and 24, respectively, said uprights having journaled thereon sprocket-wheels carrying chains 25 and 26, which run in paths over the 10 beams 13 and 14. The chains over each beam are disposed parallel and the sprocket-chains are so fixed that they may be readily adjusted on their respective uprights to raise or lower the chains in accordance with the height of the 15 corn operated upon, the object of said chains, which are provided with outwardly-projecting fingers 27, being to catch the cornstalks operated upon after they are erected by the snouts and picker-wheels and maintain such 20 erect positions while they are passing through the crushing mechanism to the knives and backward onto the receiving-table behind the knives. The uprights above mentioned each have a rearward incline, as will be noted, so 25 that the lower chains will first release the corn and subsequently the upper chains, which latter will carry the corn and will tilt it onto the table.

To revolve the picker-wheels 18 and 19, the 30 rearward extensions of their respective shafts are provided with sprocket-wheels 28' and 29', respectively, carrying chains extending rearwardly and passing over sprocket-wheels on a drive-shaft 29, which said shaft is energized from the traction-wheels of the 35 machine through any desired mechanism or from any other source of power.

It will be readily understood that we may 40 employ shafts and miter-gearing in the place of the chains without departing in any way from the spirit of our invention. Motion is contributed to the chains 25 and 26 from the shaft 29 through the medium of bevel-gears 30 and 31, which engage similar gears on the 45 standards 23 and 24, which are journaled in suitable bearings on the beams 13 and 14.

Intermediate the rear extensions of the picker-wheels 18 and 19 and the knives 10, 11, and 12 is arranged mechanism for crushing 50 or otherwise altering the structure of the corn at the point of cutting, which alteration may, however, extend above and below said point. While we have used the term "crushing" both in the specification and claims as descriptive 55 of the treatment of the stalk before cutting, the operation of the mechanism employed by us is not necessarily a crushing operation, for, as will be readily understood, we may employ mechanism for beating the stalk in 60 order to split it or any other means for macerating, masticating, or reducing in any way the resistance of the stalk to the cutter-knives by altering its structure. To accomplish this, we may employ rolls 32 and 33, pivoted in 65 suitable journals to revolve in a common horizontal plane, the adjacent points of their peripheries being so close as to crush the

cornstalks previous to the cutting operation, so that the knives may readily accomplish their purpose. Both rolls may be positively 70 driven or one roll may be arranged as an idler, as shown, and the other roll be driven positively through the medium of a sprocket-chain leading from the shaft 29 and passing over a sprocket-wheel on a shaft 34, having 75 a bevel-gear engaging with a similar gear on the roll or its shaft. To facilitate the operation of these rolls, their peripheries may be milled, as shown, and to insure the ready 80 passage of the corn between them they may be provided with fingers 35, curved backwardly, which act upon the cornstalks and carry them between the contiguous portions of the peripheries of the rolls.

It will be understood that, if desired, disk 85 cutters or any other suitable form of cutters may be employed instead of the knives herein shown, which said knives merely indicate one arrangement, our invention being the employment of crushing mechanism arranged to operate before or simultaneously with the cutting mechanism.

It being desirable at times to vary the pitch of each finger of the picker-wheel and also the distance of its tip from the center of the 95 wheel, as hereinbefore intimated, we have provided a construction (illustrated in Fig. 4 of the drawings) which readily allows of this manipulation. In this construction 40 represents a wheel having on one face a projection 100 41, provided with preferably equidistant perforations adapted to receive the shanks of a series of fingers 42, so that they may be readily adjusted back and forth, as well as rotated. In order to clamp these fingers in their 105 adjusted positions, a clamp 43 is held against the fingers through the medium of bolts 44, passed through suitable perforations in the wheel, said ring clamping the fingers in their respective positions firmly against the 110 wheel 40.

It will be readily understood that the particular mechanism herein shown may be varied without departing in any way from the 115 spirit of our invention, such mechanism simply indicating a single embodiment of each feature thereof.

While we have claimed, in combination with the cutting mechanism, a chain for passing the material to the cutting mechanism and picker-wheels operated in substantially vertical planes, it will be readily understood that this specification of the arrangement of said 120 picker-wheels is intended to distinguish them from a horizontal arrangement, as well as any other position in which they would be capable of performing the function incident to the 125 combination expressed in said claim.

Having now described our invention, what we claim is—

1. In a harvester, the combination with the cutting mechanism of crushing mechanism arranged in advance of the cutting mechanism to crush the material to be operated upon 130

- at the point of cutting, previous to the engagement of the cutting mechanism.
2. In a harvester, the combination with cutting mechanism of crushing mechanism arranged in advance of the cutting mechanism to engage the material to be operated upon at the point of cutting and to crush it previous to the engagement of the cutting mechanism.
3. In a harvester, the combination with cutting mechanism of crushing-rolls arranged in advance of the cutting mechanism to crush the material to be operated upon at the point of cutting, previous to the engagement of the cutting mechanism.
- 15 4. In a harvester, the combination with cutting mechanism of crushing-rolls arranged in advance of the cutting mechanism to engage the material to be operated upon at the point of cutting, and crush it previous to the engagement of the cutting mechanism.
5. In a harvester, the combination with cutting mechanism of crushing-rolls arranged in advance of the cutting mechanism to crush the material to be operated upon at the point of cutting previous to the engagement of the cutting mechanism, said rolls being arranged to move with the harvester transversely of said material.
- 25 6. In a harvester, the combination with cutting mechanism of corrugated crushing-rolls arranged in advance of the cutting mechanism to crush the material to be operated upon at the point of cutting, previous to the engagement of the cutting mechanism.
- 35 7. In a corn-harvester, the combination with cutting mechanism of corrugated crushing mechanism arranged in advance of the cutting mechanism to crush the material to be operated upon at the point of cutting previous to the engagement of the cutting mechanism.
- 40 8. In a device of the class described, a picker-wheel having bent fingers pivoted thereto and a clamp adapted to clamp said fingers rigid.
- 45 9. In a device of the class described, a picker-

wheel having bent fingers pivotally connected thereto and longitudinally movable with respect thereto, and means for clamping said fingers in fixed positions.

10. In a device of the class described, the combination with cutting mechanism of a chain provided with longitudinal projections arranged to engage the material to be operated upon and pass it to the cutting mechanism, picker-wheels extending below the chains and operating in substantially vertical planes, to erect the material and pass it to the chain and inclined snouts arranged in advance of the picker-wheels to give the said substance an initial movement from a reclining position to be engaged by the picker-wheels.

11. In a corn-harvester, the combination with the cutting mechanism of means arranged in advance of the cutting mechanism to reduce the resistance of the material at the point of engagement of the cutting mechanism and feed the material in the direction of the cutting mechanism.

12. In a corn-harvester, the combination with the cutting mechanism of mechanism having additional motion to the ground motion of the harvester and operating to alter the structure of the material operated upon at the point of engagement of the cutting mechanism, said mechanism gripping and feeding the material against the ground motion of the harvester.

In testimony whereof we affix our signatures in presence of two witnesses.
